UNITED STATES PATENT OFFICE.

ALFRED JOHNSON, OF CHICAGO, ILLINOIS, ASSIGNOR TO ALFRED JOHNSON SKATE CO.,
A CORPORATION OF ILLINOIS.

DESIGN FOR A CUP, TROPHY, OR ARTICLE OF SIMILAR NATURE.

57,130.

Specification for Design.

Patented Feb. 22, 1921.

Application filed June 25, 1919. Serial No. 306,748. Term of patent 7 years.

To all whom it may concern:

Be it known that I, ALFRED JOHNSON, a citizen of the United States, and residing at the city of Chicago, county of Cook, and State of Illinois, have invented a new, original, and ornamental Design for a Cup, Trophy, or Article of Similar Nature, of which the following is a specification, reference being had to the accompanying drawing, forming a part thereof.

This invention has for its object a novel design for a cup or trophy and similar articles.

In the drawings:

The figure is a view of the front elevation of a cup or trophy illustrating the design embodying my invention.

As shown in the drawing:

The design consists of a cup or bowl, attached to the side of which is a plurality of handles fashioned so as to resemble ice skates. The cup or bowl is ovoid in shape and is ornamented with a raised or carved decoration.

I claim:

The ornamental design for a cup, trophy or article of similar nature, substantially as shown and described.

In testimony whereof I have hereunto subscribed my name at Chicago, Cook county, Illinois, this 12th day of March, 1919.

ALFRED JOHNSON.
